(57) **CLAIM**

I claim the ornamental design for a charger, as shown and described.

DESCRIPTION

FIG. 1 is a front perspective view of a charger according to the present invention;

FIG. 2 is a front view of the charger of FIG. 1;

FIG. 3 is a rear view of the charger of FIG. 1;

FIG. 4 is a left-side view of the charger of FIG. 1;

FIG. 5 is a right-side view of the charger of FIG. 1;

FIG. 6 is a top view of the charger of FIG. 1; and,

FIG. 7 is a bottom view of the charger of FIG. 1.

All broken lines shown in the drawings are for environmental purposes only and form no part of the claimed design.

1 Claim, 4 Drawing Sheets---
